UNITED STATES PATENT OFFICE.

OSKAR JUNGHANS, OF SCHRAMBERG, GERMANY.

POCKET-LAMP GENERATOR.

1,303,068.

Specification of Letters Patent.

Patented May 6, 1919.

Application filed October 10, 1916. Serial No. 124,916.

To all whom it may concern:

Be it known that I, OSKAR JUNGHANS, a subject of the King of Wurttemberg, residing at Schramberg, Wurttemberg, Germany, have invented certain new and useful Improvements in Pocket-Lamp Generators, of which the following is a full, clear, and exact description.

This invention relates to improvements in 10 pocket electric lamps and aims to provide improvements therein.

The present invention provides a simple construction, rendering itself very suitable to manufacturing conditions, wherein the 15 magnet is combined with plates to constitute the casing of the device. The plates act to support the moving parts independently of the magnet, whereby no adjustments between the magnet and working parts carried 20 by the plates are necessary. The magnets, being of hardened steel, are difficult to make of uniform dimensions.

In the accompanying drawing a constructional form of the lamp according to the 25 present invention has been exemplified in Figures 1 to 6.

In said drawings,—

Fig. 1 is a cross-section of the lamp;

Figs. 2 and 3 are plan views (from opposite sides) of the lamp;

Fig. 4 is a partial longitudinal sectional view at the pole end of the lamp;

Fig. 5 is a perspective view of the plates which carry the working parts and form the 35 casing with the magnet;

Fig. 6 is a perspective view of the magnet.

As may be seen in particular in the vertical cross section Fig. 1 a separate body frame g , i is arranged between the branches 40 of the magnet m ; in this frame the whole gearing is, similarly to a clock work, journaled together with the operating lever and the armature. This body frame is composed essentially of the two face plates g , i , and is 45 covered at the top and the sides by the magnet yoke, so that the said frame with the parts fitted thereto may be readily fitted as one piece between the branches of the magnet. With the constructional form shown 50 in the accompanying drawings the frame may be inserted into the magnet from above, owing to the upper plate i being made so wide that it overlaps the edges of the magnet branches, while the lower plate g is a 55 little narrower than the distance between

said magnet branches. For insuring a close cover a separate cover plate h is provided on the narrow plate g , and screwed thereto, and overlapping the branches of the magnet. In consequence of this arrangement it 60 is possible to assemble the whole gearing together with the armature outside of the magnet and subsequently fit it into the magnet. As hereinbefore stated the frame is, when thus fitted into the magnet, encircled 65 and closed at the top (where the bulb is attached) and at the two sides, by the magnet and thus covered. Below the frame is closed by means of a fitting b made of some non-magnetic material, such as zinc or brass, 70 which is screwed to the plates g , i and has the object of insuring the proper distance of the pole shoes m^1 . If the magnet is left to itself, this distance between the pole shoes 75 will differ frequently; by the fitting b , however, the pole shoes are held at the proper distance, so that the said fitting serves both as a spacing member and as a cover for the magnet yoke and the frame, so that the apparatus which has been assembled by fitting 80 the frame into the magnet forms one compact body, closed on all sides and of a convenient, handy shape.

In the embodiment shown in the drawings the said fitting b is formed with bearing surfaces b^1 , against which bear the pole ends, while the two wings b^2 of said fitting overlap the pole shoes on the outside, where they are screwed to the magnet.

As shown in Fig. 2 the upper plate, which is made of zinc, has a peculiar shape. All bearing holes are formed in a piece of iron r laid along the middle line of this plate, which piece of iron is, in its details made the same as the bushes employed in the previous 95 constructions of the apparatus. On the same middle line is provided at the top a hole, which registers with a hole in the fitting b , and is adapted to receive a screw c screwing into the latter whereby the bearing of the armature which, as said before, is likewise on the said middle line, is fixed in a longitudinal direction. For securing the position of said bearing also laterally, the plate is provided at e and e^1 with curved 100 projections, the curves of which are part of a circle having its center on the same central line of the plate. In wholesale manufacture the magnet is first bent, so that it has the shape shown in the drawing (Fig. 6). 110

Then the fitting b (Fig. 4) is screwed to the magnet and the circle enveloping the armature is ground out to the diameter f (Fig. 4). The magnet is thereupon again 5 ground out to a circular curve at a given distance from the center of the diameter f so as to correspond with the projections e . It is a simple matter to insure that the center of the ground circle of the diameter f 10 and the center of the ground out circle at the diameter e are at a given distance from each other. When, thereafter, the gearing is fitted into the magnet, it is obvious that not only such gearing, but in particular the armature is secured in their position by the 15 three points c , e , and e^1 , so that the gap between the armature and the poles of the magnet must be even all over and the limits may be reduced.

20 The construction of the lamp described hereinbefore therefore affords the following advantages:

1. The magnet and the body frame with the works may be manufactured separately 25 and be subsequently assembled without any further fitting being necessary.

2. The position of the armature relatively to the magnet is fixed in such a manner, that the gap between the armature and the poles 30 of the magnet may be made of the smallest possible size.

As, now, it is no more necessary for the magnet to receive any pins or screws for securing the side plates, the edges of the magnet 35 may be well rounded off, and this will render the holding of the lamp more agreeable to the hand of the user. By the armature being approached to the magnet, it is, furthermore, possible to obtain such electric 40 force that even at a single pressure on the operating lever, the lamp will light up satisfactorily for several seconds. By the employment hereinbefore described arrangement, by which the center of the armature 45 is fundamentally assured, it will be possible to reduce, with increasing experience in manufacture, the gap between armature and magnet to but a few tenths, and thereby considerably increase the efficiency of the lamp.

50 I claim:

1. A hand generator consisting of two parts, one of said parts comprising an armature and driving gear therefor, the other part comprising a magnet, the said 55 two parts being constructed to be fitted as

a unit one within the other to form a unitary closed structure.

2. A hand generator consisting of two parts, one of said parts comprising an armature and driving gear therefor, the other 6 part comprising a magnet and a part attached thereto for holding the poles of the magnet a constant distance apart, and closing the space between the ends of the magnet, the said two parts being constructed to 65 be fitted as a unit one within the other to form a unitary closed structure.

3. A hand generator consisting of two parts, one of said parts comprising an armature and driving gear therefor, the other 70 part comprising a magnet and a part attached thereto for holding the poles of the magnet a constant distance apart, and closing the space between the ends of the magnet, the said two parts being constructed to 75 be fitted as a unit one within the other to form a unitary closed structure, said first-named part further comprising two side plates fixed in spaced relation to one another, and between which the armature and 80 gears are arranged, and said side plates having corresponding bearing plates fixed thereto, the bearings for the rotatable parts being carried by said bearing plates.

4. A hand generator consisting of two 85 parts, one of said parts comprising an armature and driving gear therefor, the other part comprising a magnet and a part attached thereto for holding the poles of the magnet a constant distance apart, and closing 90 the space between the ends of the magnet, the said two parts being constructed to be fitted as a unit one within the other to form a unitary closed structure, said first-named part further comprising two side 95 plates fixed in spaced relation to one another, and between which the armature and gears are arranged, and said side plates having corresponding bearing plates fixed thereto, the bearings for the rotatable parts being 100 carried by said bearing plates, said magnet having a lamp mounting thereon.

In witness whereof, I have hereunto signed my name in the presence of two subscribing witnesses.

OSKAR JUNGHANS.
